UNITED STATES PATENT OFFICE.

JOSEPH FORSHEIM, OF NEW YORK, N. Y.

DESIGN FOR A CHARM.

SPECIFICATION forming part of Design No. 31,062, dated June 27, 1899.

Application filed March 22, 1899. Serial No. 710,105. Term of patent 31 years.

To all whom it may concern:

Be it known that I, JOSEPH FORSHEIM, a citizen of the United States, and a resident of New York, in the county and State of New York, have invented and produced a new and original Design for Charms, of which the following is a specification, reference being had to the accompanying drawing, forming a part thereof.

The leading features of my design consist in a charm presenting a small ring, a bifurcated body the periphery of which is formed of irregular curved lines, the branches of the body being pointed, and the image of a child presented at one side of the body.

In the accompanying drawing, A represents the ring. B represents the bifurcated body, b b' the branches thereof, and C represents the image of the child.

What I claim is—

The design for a charm, substantially as shown and described.

In testimony that I claim the foregoing as my invention I have signed my name, in presence of two witnesses, this 14th day of March, 1899.

JOSEPH FORSHEIM.
